UNITED STATES PATENT OFFICE.

MYRON F. HILL, OF NEW YORK, N. Y., ASSIGNOR OF ONE-HALF TO EDWARD E. CLEMENT,
OF WASHINGTON, DISTRICT OF COLUMBIA.

TELEPHONE-EXCHANGE SYSTEM AND APPARATUS THEREFOR.

1,322,170.

Specification of Letters Patent. Patented Nov. 18, 1919.

Original application filed March 24, 1908, Serial No. 423,051. Patent No. 1,253,688. Divided and this application filed January 10, 1918. Serial No. 211,236.

To all whom it may concern:

Be it known that I, MYRON F. HILL, a citizen of the United States, residing at New York, in the county of New York and State 5 of New York, have invented certain new and useful Improvements in Telephone-Exchange Systems and Apparatus Therefor, of which the following is a specification, reference being had therein to the accompanying 10 drawing.

My invention relates to telephone exchanges, and has for its object the reduction of the wiring and apparatus and the resulting simplification of the exchange.

15 My invention consists in the substitution of a few circuits controllable by a large number of subscribers for the individual circuits heretofore used in such a way that any person may control at all times one of the 20 few common circuits. More particularly my invention consists in an exchange in which the subscribers are divided into groups preferably of about one hundred each, each group provided with a number of trunk lines 25 reaching from the central exchange to short individual circuits, which in turn are connected to the subscriber's station.

For the busiest groups of subscribers fifteen or twenty trunk lines are required, 30 while for the suburban groups but a few trunk lines are required, perhaps not more than eight or ten.

This present application is a division of my co-pending application filed March 24, 35 1908, Serial No. 423,051, issued Jan. 15, 1918, as Patent No. 1,253,688, in which all matters disclosed and not claimed will be claimed herein.

For each group the trunk lines are divided 40 into two sets, one of receiving trunk lines and the other of transmitting trunk lines. The receiving trunk lines are connected to a single board of the multiple switch board central station. When any subscriber of a 45 group takes his telephone off from its hook, his individual short circuit is automatically connected to one of the idle receiving trunk lines, and this connection operates an indicator at the board to which the receiving 50 trunk line is connected, informing the operator that a subscriber desires a connection. The operator then finds out the number of the desired subscriber, connects the receiving trunk line to a transmitting trunk line,

belonging to the group of the desired subscriber, and automatically causes, by means of a commutator at her board, the transmitting trunk line to be connected to that subscriber.

The transmitting trunk lines of each 60 group are connected in multiple to all the boards of the exchange. Any transmitting trunk line of a group may be connected automatically to any subscriber of that group under the proper conditions.

In the drawings,

Figure 1, represents in diagram view the plan of the circuits of the exchange.

Fig. 2, shows the automatic switches which 70 interconnect the subscribers' circuits and the trunk lines of a group, and the circuits by which they are controlled.

Fig. 3, shows in diagram view the connection of two transmitting trunk lines to two 75 boards of an exchange, and the substitute for a multiple switch board test circuit.

Fig. 4, shows a face view of a section of the board, to which the transmitting trunk lines of a group are connected.

Fig. 5, shows in sectional view one form 80 of an indicating spring jack.

Fig. 6, shows a vertical sectional view of a different form of an indicating spring jack.

Fig. 7, shows a sectional view of a third modification.

Fig. 8, shows a plan view of a transmitting terminal switch, and the circuits by which said switch is controlled.

Fig. 9, shows the commutator outfit of a central office operator by means of which 90 a transmitting trunk line is connected to a subscriber's circuit.

Fig. 10, shows in side view part of the circuit controller.

Fig. 11, shows an edge view of the apparatus which controls the operation of a transmitting trunk line switch.

Fig. 12, shows in side view, a transmitting trunk line switch.

Fig. 13, shows a portion of the same in 100 plan view.

Fig. 14, shows an end view of part of the commutator apparatus.

Fig. 15, shows a side view of part of the operator's cord switch with the plug removed.

Figs. 16 and 17 are modifications.

Fig. 18 is a detail.

Fig. 19 is a diagram of the telephone switch hook in normal position.

Fig. 20 is a similar view of the hook in actuated position.

5 Fig. 21 is a diagram of the mechanical line relay in one of its actuated positions.

Fig. 22 is a similar view of the relay in another one of its actuated positions.

In Fig. 1 are shown two boards of a multiple switch board exchange to which are connected receiving and transmitting trunk lines. Ts' , Ts^2 , Ts^3 are transmitting switches by means of which the transmitting trunk lines Tt' , Tt^2 and Tt^3 , are connected to short individual circuits A, A', A², B B', &c. To each of these short individual circuits A, A', A², B, B', &c., are connected subscribers' outfit like that shown in diagram view in A⁴.

The two wires a and b of the short metallic circuit are normally connected to bells a' , contact a^2 , switch lever a^3 normally connected thereto, and back to the wire b . When the telephone a^4 is switched for use, the circuit is transferred from the bells a' , 20 to the subscriber's telephone a^4 , secondary coil a^{14} , contact a^7 , and switch lever a^8 , temporarily connected thereto.

The local circuit including the contact a^7 , primary coil a^6 , transmitter a^5 , battery a^9 , 25 and contact a^{20} is closed at the same time.

The two wires are open to each other while the switch lever a^3 is in transit between the contacts a^2 and a^7 . When the telephone is removed from the hook the usual automatic 35 spring device causes the heel contact a^8 of the switch lever to strike the insulated contact a^9 , on the lever a^{12} , thus grounding the wire b , through the switch lever a^3 , heel contact a^8 , insulated contact a^9 , condenser 40 a^{10} , and ground at G.

The lever is then released and the projection a^{11} of insulating material prevents the contact a^9 from touching the contact a^{13} . When the telephone is restored to its hook, 45 the contact a^{13} insulated from but mounted upon the switch lever a^3 , comes into contact with the lower surface of lever a^{12} , thus grounding the wire a , through the tension spring a^{21} . When the hook is released the 50 insulated projection a^{11} prevents a connection between the contacts a^8 and a^9 . Thus when the rear end of the switch hook lever a^3 moves downward, the metal at a^8 engages the contact plate a^9 without striking the metal at a^{11} ; and when the rear end of the 55 lever a^3 moves upward, the contact plate a^{13} engages the metal a^{11} without striking the plate a^9 .

The telephone a^4 has a flexible cord supported a^{15} , secured to a contact spring a^{16} , adapted while the telephone is suspended therefrom to make contact with the contact point a^{17} , thus closing the circuit of the bells a' , in a shunt around the telephone circuit a^4 , 60 a^{14} , while the telephone is switched for use.

The purpose of this device will be seen later. The wires a , b , of the short individual metallic circuit, are connected by multiple branches c and d to each receiving switch Rs and transmitting switch of the group to which the 70 subscriber belongs. These connections are shown in Figs. 1 and 2. The form of switches in Fig. 2 is preferred. Those in Fig. 1 are simplified to better illustrate line circuits.

The branches c and d are connected to the contacts c' and d' , on each switch. On each switch are ring contacts c^2 and d^2 in juxtaposition to the contacts c' and d' , and adapted to be connected thereto by the contacts c^3 and d^3 respectively, mounted upon the circuit closing lever of each switch. To the ring contacts c^2 and d^2 are connected two wires c^4 and d^4 of the metallic circuit of each trunk line.

The connection between a subscriber's metallic circuit and a receiving trunk line Rt is effected as follows: When the subscriber removes his telephone from its hook thus switching it for use, a circuit is closed 90 from the ground G, condenser a^{10} , contacts a^9 and a^8 , switch lever a^3 , line conductor b , to the automatic sub-central switches, individual branch wire e , coil e' , contacts e^2 , conductor e^3 , common to all the subscribers 95 of the group, conductor e^5 , to the central exchange, current generator D, and ground G.

Upon the energization of e' current from the battery B energizes the relay e^4 , over the circuit including relay e^4 , resistance e^{11} 100 (about equal to that of the magnet e^{24}), contacts e^{39} , e^{20} , resistance e^{37} , thus releasing the escapement e^{46} of the weight or motor e^{36} .

The motor e^{36} propels at a regular speed 105 the shaft f , upon which are mounted the receiving and transmitting switches Rs' , Rs^2 , Ts' and Ts^2 .

A resistance e^{57} graduates the amount of current supplied to the relay e^4 .

The alternating current on the circuit just traced energizes the coil e' as shown in Fig. 21, which produces a change in the circuits, so that the subscriber's line will secure a connection to one of the receiving 115 trunk switches but no other. As the coil e' is energized, its core attracts the armature of lever e''' . Since the upper end of lever e''' is in contact with the contact plate e^2 mounted on the lever e^{38} it slides on a plate which acts as a cam lifting the lever e^{38} until the upper end of the lever e''' leaves the plate e^2 . Then the lever e^{38} drops again, its insulating plate e^{381} resting on an upper end of the lever e''' , and the metal 125 of the lever resting against the rear of contact e^{39} . At the same time, when the coil e' attracts the lever e''' , a contact portion on the front of contact e^{39} engages the spring contact e^{20} , and the rear portion 130

of the contact e^{39} is withdrawn from contact with the back contact e^{25} . From this mechanical operation it will be seen how the following electrical circuits are established; their object being to connect the subscriber's line to a receiving trunk line exclusive of any other trunk line connection.

From one pole of battery B by way of magnet e^4 , resistance e^{11} , of which there is 10 preferably one individual to each subscriber, contacts e^{38} and e^{39} now closed, wire e^{13} , branch wire e^{14} , of switch Rs^2 for example, contact e^{15} , individual to the subscriber's circuit, (see Fig. 8), brush contact i' , coils 15 i^2 of the magnet operating the circuit closer h , wire i^3 , brush contact i^4 , ring contact e^{16} , common to the sets of contacts of all the subscribers of the group, wire e^{17} , containing contacts e^{18} normally closed, there being 20 a separate wire e^{17} and separate contacts e^{18} , for each receiving switch, wire e^{19} , to battery B.

The same circuit might be traced through any other receiving switch belonging to 25 this group in case its traveling arm and contact brushes reach the subscriber's terminals first.

The sets of contacts belonging to each subscriber are so arranged with relation to 30 the normal position of the circuit closers h of the various switches, that no two circuit closers will be in position to make contact with the subscriber's line simultaneously.

To effect this the sets of contacts of a 35 subscriber's line, line ab for example, are arranged in the same vertical line, while the normal positions of the circuit closers h are arranged spirally, or at different points around the shaft f .

Presuming that the circuit closer h and switch arm h' of the switch Rs^2 , make connection with the contacts of line ab , the coils i^2 of the magnet will attract the armature h^2 , operating the circuit closer h so 45 that the contact c^3 crosses the contacts c' and c^2 , the contact d^3 crosses the contacts d' and d^2 , and the contact i^7 makes connection with the individual switch board 50 contact e^{21} , closing the following parallel circuits:

From one side of the coils i^2 through wire i , contact i^7 , contact e^{21} , branch wire e^{22} , wire e^{23} , coil e^{24} , individual to each subscriber, to battery B. The rest of this circuit is the same as previously traced over wire e^{19} .

The coil e^{24} when energized opens the 60 temporarily closed contacts e^{38} and e^{39} by lifting the armature. This releases the armature and contact e^{39} by removing the stop contact e^{38} , which has been engaged with the contact e^{39} , so that it falls back to its normal position except that it does 65 not strike contact e^{25} on account of the in-

sulated back stop e^{47} interposed by the lifted armature as shown in Fig. 22. When e^4 is deenergized by the retraction of lever e''' of magnet e' , the shaft f stops.

The contacts e^2 are opened before the contacts c^3 and d^3 of the circuit closer h cross connect the contacts c' , c^2 and d' , d^2 .

The contacts e^{25} and e^{39} when held open, as described, prevent a transmitting switch Ts' , or Ts^2 from making connection with 75 this line.

Thus it will be seen after any subscriber's circuit a , b , has been connected to a receiving switch, Rs^2 for example, no other receiving switch Rs' , or transmitting switch 80 Ts' , or Ts^2 , can be connected to it.

The circuit of the subscriber's line a , b , when thus connected is continuous through the two limbs c^4 and d^4 of the receiving trunk Rt^2 to the central station (see Fig. 1), where 85 these limbs are connected, through intermediate switch apparatus controlled by the operator, to the two contacts c^6 and d^6 of a connecting plug P.

If the subscriber's line a , b , had been connected to any other trunk line of the group, Rt' , for example it would have been connected to another plug, through another set 90 of switching apparatus controlled by the same or another operator, who may be stationed at board No. 2, or elsewhere.

If a subscriber of another group had taken his telephone off his switch, subscriber No. 309 for example, connected to line B^2 , he would have been connected to a receiving 100 trunk line Rt^3 for example, and thus connected to a plug P controlled by an operator at board No. 3, as shown.

It will be noticed that the short individual 105 metallic circuits A , A' , A^2 and A^3 belonging to subscribers No. 201, No. 241, No. 242 and No. 243 may be connected through receiving trunk lines Rt' , and Rt^2 , to switch plugs P under the control of an operator at board No. 2. These subscribers' lines are 110 but a few of the large number, one hundred for example, which may be connected through these switches Rs' and Rs^2 . There may be additional switches Rs and corresponding additional trunk lines Rt , to which 115 the same subscribers' lines may be connected.

In like manner the short individual metallic circuits belonging to subscribers No. 309, No. 310, No. 311, No. 322 and No. 313, lettered B^4 , B^5 , B^6 , B' and B may be connected through one or more receiving switches Rs^3 to one or more receiving trunk lines Rt^3 , and thence to plugs P at central. The subscribers' lines referred to are but a few of the number that may be employed. 120 Preferably however there are one hundred or less subscribers' lines adapted to be connected to plugs P at board No. 3.

In like manner I divide all the subscribers 125 of the exchange into groups of one hundred 130

or less each, and so connect the subscribers' lines of each group, to switches and trunk lines that the lines of each group may be connected to any section of the central switch board preferably that individual to the group. All the subscribers having numbers under one hundred are connected to board 0, all subscribers numbered 100 or over and under 200 are connected to board No. 1, all 5 subscribers numbered 200 and over and under 300 are connected to board No. 2, and so on. This relation between the number of the subscriber and the number of the board at central is not necessary but is more convenient. Except for convenience sake this arrangement is entirely unnecessary. And the system will work quite as well if the receiving trunk lines are distributed among the various boards so as to even up the work 10 of the operators. Receiving trunk lines from several groups of subscribers might be connected to a single board under the supervision of a single operator. When applied to an exchange system in which the 15 multiple switch board feature is not used, all the trunk lines would be supervised at a single board.

The groups of subscribers may if desired have any desired number of circuits as long 20 as each group has a different designating character from any other group.

The connection between a subscriber's line A and a receiving trunk line R² has been described. A complete metallic circuit is 25 established through the subscriber's conductors a and b to the trunk line conductors c² and d². This circuit is normally completed through the contact springs c¹, d¹, contact springs c², d², annunciator c¹³, and impedance coils d¹¹, leading to an alternating current generator CG which will be described later. There is a separate generator for each receiving trunk line. The current is of such a character that it will energize the coil c¹³, 30 causing the annunciator c¹³ to attract its flap in such a way as to display its signal, informing the operator that a call has been sent in from some subscriber of the two hundreds group over the trunk line R². Incidentally the pairs of contacts c¹² and d¹² are closed but at present this has no function. These contacts are closed by the two armatures, one at each end of the coil c¹² being drawn up against the front contacts c¹² 35 and d¹².

When the operator sees the annunciator c¹³ display its signal she lifts the plug P from the base P', upon which it is normally supported causing the release of contact springs c¹ and d¹ so that they may come into contact with the contacts c¹⁰ and d¹⁰ as shown at board No. 3. This connects the two trunk line conductors c² and d² to the operator's telephone set P², constructed in the 40 usual manner, supplied with a transmitter

current from battery B'. Thus a conversation circuit is established from the subscriber to the operator. The subscriber informs the operator with whom he desires to be connected, subscriber No. 322 for example. 70

The operator then inserts the plug P into the spring jack of an outgoing transmitting trunk line, T² for example, adapted to be connected through a transmitting switch T² to the short outlying metallic circuit 75 of subscriber No. 322. This connection is established automatically as will now be described.

It will be noticed that when the plug has been withdrawn from its resting place the contact springs c¹ and d¹ have left the contact springs c⁸ and d⁸ which in turn have separated from and released the contact springs c⁹ and d⁹ so that the latter make connection with the normally disconnected 80 contact points c¹¹ and d¹¹ electrically connected to the commutator contacts c¹⁴ and d¹⁴. Thus the two contacts c⁹ and d⁹ of the plugs P are connected through the contact springs c⁹ and d⁹, contacts c¹¹ and d¹¹, to the 85 commutator contacts c¹⁴ and d¹⁴. In connecting to a transmitting trunk line the operator has connected to the group to which the called subscriber belongs. All that remains for the operator to do is to select the 90 particular subscriber of the group to which the trunk line is to be connected. This she accomplishes by means of the commutator C, key-boards O', and plug P². These elements make up her commutator outfit. Upon the cylinder O which is made of insulating material in the modification which is being described, are mounted contact strips g' of 95 variable lengths of conducting material.

These contact strips g' are so arranged 100 with relation to the contact springs c¹⁷ that but two strips are adapted to touch all the contact springs c¹⁷, three strips adapted to touch nine contact springs, four strips adapted to touch eight contact springs, and so on, so that each contact spring c¹⁷ is adapted to be connected through the strips g' to the contact spring c¹⁴ a different number of times.

The contacts d¹⁷ bear the same relation to 110 the strips g' as do the contact springs c¹⁷. For groups of one hundred subscribers there are ten contact springs c¹⁷, ten springs d¹⁷, and eleven strips g' normally disconnected therefrom. The contact springs c¹⁷ and d¹⁷ are connected to insulated cross bars c¹⁸ and d¹⁸ as shown. The plug P² grounded at G is adapted to be connected to a single cross bar c¹⁸ and a single cross bar d¹⁸ thereby connecting them both to ground. In 115 connecting to subscriber No. 322 the operator places the plug P² upon the cross bars 120 c¹⁸ at their junction and rotates the cylinder once in the direction of the arrow.

The cylinder is rotated in such a direc- 125

tion that each strip g' touches a contact spring or springs d^{17} and after leaving these springs touches one or more contact springs c^{17} . The last strip g'' which passes under all the contacts c^{17} and d^{17} is so formed that it touches the contact spring c^{17} while it touches the contact spring d^{17} , thus simultaneously cross connecting these springs. When the plug P^6 has been placed upon the cross bars 2 of the sets of cross bars c^{18} and d^{18} , and the cylinder C rotated once as described, the contact springs c^{17} and d^{17} connected to those two cross bars are connected to the contacts c^{14} and d^{14} by the four longest strips successively as described, establishing the following circuits, which may be traced upon Figs. 1 and 2: from ground G through the alternating current generator D, a supply wire e^5 reaching to the sub-central to which line No. 322 is connected, thence through contacts e^{33} , condenser e^4 to the relay e^9 , wire e^{32} , including the set of normally closed contacts n , (the order of the relays and contacts being immaterial) thence by trunk line conductor d^4 , to spring jack contact d^5 , plug contact d^6 , contact spring d^9 , contact point d^{11} , wire d^{19} , contact d^{24} , one of the contact springs d^{17} , the one connected thereto by 20 the cross bar 2, of the set designated d^{18} , thence by way of plug P^6 connected thereto, to ground at G. This circuit is made and broken four times by the strips g' of the commutator. The relay e^9 is energized 25 four times. Referring now more particularly to Fig. 2, it will be seen that when the relay e^9 is energized it accomplishes two functions, in connection with the selecting and controlling apparatus there shown, which is located at the sub-central station to 30 which the called line is connected.

Not only does it actuate the ratchet movement m^8 of the units switch but it actuates the circuit controller C². When the armature of relay e^9 is drawn down, its heel e^6 forces the link e^2 upward, which in turn tilts the rocker e^{34} against the offset m^8 . This offset is rigidly connected to the ratchet wheel operated by the pawl m^6 and resists 45 the rocker e^{34} , so that the rocker which is pivoted on the pawl m^6 lifts the pawl upward. As seen in Fig. 10, it catches the next tooth of the ratchet wheel and when the relay e^9 is deenergized, the controller C² is advanced one step. With it travels the offset m^8 , which travels downward and no longer resists any oscillations of the rocker e^{34} , and this operation is not repeated.

This local circuit is closed four times as 60 stated. The first time that the magnet e^9 is energized, the circuit controller C² closes the contacts n' , n^3 and n^6 through the respective contact plates. The operation of the circuit controller C² by the second and 65 third closing of this circuit is prevented as

described. The functions of these sets of contacts will shortly be described.

When the circuit is closed four times the relay e^9 operates the ratchet mechanism m^8 , propelling the contact arm m^9 around to contact No. 2 on the units switch m^{10} .

As has been described after a strip g' has left a contact spring d^{17} it makes contact with a spring c^{17} , grounding the "c" side of the circuit as follows:—

From ground at G, current generator D, supply wire e^5 , contacts e^{31} normally closed, condenser e^8 , relay e^7 , contacts n^3 , closed as described, trunk line conductor e^4 , jack contact e^5 , plug contact e^6 , contact spring c^9 , 80 contact point c^{11} , commutator contact c^{14} , strips g' , contact spring c^{17} connected to bar c^{18} numbered 2, plug P^6 , and ground G. This circuit is also energized four times.

The relay e^7 therefore attracts its armature four times thus actuating the ratchet mechanism m^{11} and propelling the contact arm m^{12} around to contact No. 2 of the tens switch.

The fourth time that the circuit is closed, 90 the relays e^7 and e^9 attract their armatures together and thus by means of the heels e^6 and links e^8 force upward both ends of the rocker e^{34} , forcing the pawl m^6 upward so as to catch the next tooth of the ratchet n'' . 95 When the relays are deenergized the rocker and pawl are released, and operate the controller another step, bringing it to its third and last position. Thus it opens the contacts n and n^3 and closes contacts n^4 and n^5 100 by altering the position of the respective contact plates n , n^3 , n^4 and n^5 . It is to be noted that the pawl m^6 acts on its back stroke and not on its forward stroke. Its back stroke in the diagrammatic illustration 105 of Fig. 2 is the downward stroke, but this showing is for convenience of diagram only, since in the practical apparatus shown in Figs. 10 and 11 the back stroke of pawl m^6 is an upward stroke.

The closing of contacts n^5 establishes a circuit from the grounded direct current generator D³ over the supply wire e^{61} through the restoring magnet M⁴ to the trunk line conductor e^4 . When this line is connected 115 to ground by a subscriber or by an operator, the magnet M⁴ attracts its armatures m^{17} and by means of mechanical connections, m^{18} , for example, withdraws the detents m^{19} and m' permitting all the switching apparatus to be restored to its normal position.

When the armature m^{17} is attracted the insulated wedge m^{20} opens the contacts e^{31} and e^{33} . This prevents relay e^7 for example, from being operated while the circuit controller C² is returning to its normal position. The magnet M⁴ being operated whenever the "c" side of the conversation circuit is directly grounded is operated when a switch board operator closes contacts c^{19} for exam- 130

ple, or whenever a subscriber hangs his telephone receiver upon its switch, thereby causing the contacts a^{13} and a^{12} to come into electrical connection, grounding the conductor 5 a directly through spring a^{21} . When the armature m^7 is attracted by the restoring magnet M^4 , it closes the set of contacts m , grounding the circuit including relay M^4 through wire m^2 and three branch circuits, 10 one branch m^4 containing contacts n^6 closed except when the controller C^2 is in its normal position shown, a second branch m^5 containing contacts m^{61} closed except when the ratchet m^8 is in its normal position, and 15 the third branch m^7 containing contacts m^{100} closed under similar conditions. The contacts m^{61} and m^{100} are closed when the cleft wheel attached to the ratchet carries the cleft beyond the contact spring. As long as any- 20 one of the three branch circuits is closed while restoring, the relay M^4 will keep all the detents m^{17} , m^{19} , and m' , withdrawn from their appropriate ratchets, thus insuring a return of all the switches to their 25 normal position.

Therefore whenever a subscriber hangs up his telephone the apparatus controlling a transmitting switch is restored.

To return now to the manner in which this 30 switch apparatus controls the operation of a transmitting trunk switch Ts' .

The first step forward of the controller C^2 closes the set of contacts n' as described.

This closes the following circuit includ- 35 ing magnet e^4 —battery B, magnet e^4 , resistance m^{14} , wire m^{15} , contacts n' , wire m^{16} , wire e^{19} , back to battery B. This magnet e^4 at once releases the escapement e^{46} causing the shaft or arbor f to rotate under the in- 40 fluence of the motor e^{26} , so that the transmitting switch Ts' rotates with the shaft, and is ready to close any circuit under the control of the units and tens switches.

When the contacts n^4 are closed as has 45 been described, and when the arms m^6 and m^{12} rest upon the contacts 2 of their respective switches representing subscriber No. 22, the following circuit is established:—arm m^9 , contact 2, wire m^{21} , contact e^{40} , of the 50 transmitting switch Ts' , contact i^5 , mounted upon but insulated from the switch arm h' , wire i^2 , coils i^2 , thence by way of wire i , to the contact i' , contact e^{15} of the switch, wire e^{41} , pair of contacts e^{25} , e^{39} , open while the 55 line a b is connected to any of the switches, resistance e^{11} , battery B, wiping contact e^{42} , the conducting shaft f , switch lever h' , contact i^6 , mounted upon and electrically connected thereto, ring contact e^{10} , conductor 60 m^{22} , contact 2 on the switch m^{13} , contact arm m^{12} of the switch, contacts n^4 now closed by the circuit controller C^2 by the contact plate 65 back to the contact arm m^9 .

This circuit may be closed only when the 65 switch arm h' of the transmitting switch

Ts' comes into electrical connection with the set of contacts belonging to the line a b of the subscriber No. 22 called. For the purpose of illustrating the manner in which a transmitting switch establishes a connection between a trunk line and a subscriber's line, the line a b is represented as belonging to subscriber No. 322 for example, and the group of switches Ts' and Ts^2 may be regarded temporarily as representing the automatic sub-central of the 300 group. When therefore the above circuit is established the armature h^2 of the switch Ts' is attracted causing the contacts c^6 and d^6 to cross connect the contacts c^6 and d^6 with the ring contacts c^2 and d^2 respectively. A circuit is thus established between the subscriber's line and the transmitting trunk line. Another transmitting switch Ts^2 is controlled by another trunk line Tt^2 , the local circuits of which are not shown but which are the duplicates of those connected to and controlled by the trunk Tt' . It has been described how an operator has caused a connection between a transmitting trunk line Tt and a called subscriber. It is necessary that the operator should know that this circuit has been established.

When the lifting of the plug caused the separation of the contacts c^6 and d^6 from the contacts c^7 and d^7 , the coil c^{12} released the armature opening the contacts c^{12} and d^{12} . Having operated her commutator as has already been described she tips her commutator piece P^2 pivoted at P^3 so that the insulated arms P^4 connect the contact springs c^8 and d^8 with the contact springs c^6 and d^6 and at the same time disconnecting the contact springs c^9 and d^9 from the contacts c^{11} and d^{11} . At the same time the insulated base P' disconnects the contact springs c^7 and d^7 from the contacts c^{10} and d^{10} , establishing the following circuit:—from the supply current generator CG over the wires c^{15} and d^{15} high resistance or impedances 110 and coils c^{13} and d^{13} , contact springs c^8 and d^8 , contact springs c^6 and d^6 now connected thereto, plug contacts c^6 and d^6 , jack contacts c^5 and d^5 , of the transmitting trunk line Tt^2 , through the contacts of the transmitting switch Ts^2 as described, to the subscriber's line connected thereto. When the trunk line is connected to the subscriber's line the coil c^{13} attracts the armature, closing the contacts c^{12} and d^{12} . The armature 115 or flap of the coil c^{13} informs the operator that the trunk line has been connected as desired. If connected, the current from the wires c^{15} and d^{15} operates the call device a' until the subscriber removes his telephone 120 receiver from its hook, switching the call device out of circuit.

When the contacts c^{12} and d^{12} are closed as described the receiving trunk line conductors c^4 and d^4 are connected through the 125

plug contacts c^6 and d^6 to the conductors c^4 and d^4 of the transmitting trunk, thus establishing a complete circuit for conversation. As long as this circuit remains intact 5 the indicator c^{13} informs the operator that the lines are "busy".

If however, a called subscriber is already connected to another transmitting or receiving trunk line, this trunk line described 10 cannot establish connection with him, for the reason already stated in connection with the description of the magnets e' , e^{24} , and the levers e''' and e^{38} . The operator noticing that the called subscriber is busy informs 15 the calling subscriber to this effect, and he may drop his receiver without hanging it upon its hook and wait for the called subscriber to finish his engagement. Dropping his receiver in this way leaves it hanging 20 upon the cord a^{15} thus causing the spring contact a^{16} to come into contact with the contact a^{17} closing the circuit of the call device a' in a shunt around the telephone set. When the busy called subscriber's business 25 is over his line is automatically connected to the calling subscriber's line without the intervention of the central operator, and both subscribers are called up automatically.

30 This automatic connection depends upon the condition of the circuit of the called subscriber. As long as it is connected elsewhere the contacts e^{25} are open. When this connection is dissolved the contacts e^{25} are closed, the transmitting trunk line switch T_s is operated, closing the circuit between the trunk line and the subscriber's line, energizing the coil c^{18} of the operator's outfit at central, causing this trunk line to be connected 35 to the receiving trunk line, to which the calling subscriber is connected through the contacts c^{12} and d^{12} , causing a current from the supply generator CG to actuate the call device a' , polarized bells for example, of the 40 calling subscriber. At the same time the operator is informed of this connection by the attracted flap of the indicator c^{13} .

The operator may at any time by closing the pairs of contacts c^{20} and d^{20} by means of 45 normally open key contacts cut her telephone into the circuit, to determine by listening in, the condition of the line, or to talk with either subscriber.

The indicator c^{13} indicates "busy" as long 50 as a circuit remains established, but as soon as a circuit is opened by the operator or either subscriber in disconnecting the circuits, and grounding the b -limb, this indicator releases its flap, indicating the disconnection to the operator.

When a subscriber hangs up his telephone and the restoring relay M^4 attracts the armature m^{17} which releases the ratchet mechanism of the three switches m^{18} , m^{10} and 55 C^2 as described, the plate n^4 opens the contacts

n^4 thereby releasing the armature h^2 of the transmitting switch T_s' , so that this switch disconnects the subscriber's line a , b , from the transmitting trunk line T_t' . The weight of the armature h^2 causes the catch h^3 to become engaged with a detent h^4 which causes the arm h to be carried around again, by the shaft f which is turning under the influence of the motor e^{36} . When the transmitting switch closed the circuit between the subscriber's line a , b , and the trunk line T_t^2 , the contact i^7 coming into contact with the contact c^{21} closed a parallel circuit from the wire i' , through the relay e^{24} to the battery B, opening the contacts e^2 and e^{25} 80 and e^{39} .

The opening of contacts e^2 prevents the subscriber from getting a different connection while connected with. The opening of contacts e^{25} and e^{39} prevents another 85 trunk line T_t from being connected to the same subscriber, so, that while two subscribers are connected together for conversation by an operator their circuit cannot be interrupted or interfered with by another 90 subscriber or any other operator or the same operator over another trunk line. When the operator who has established the circuit closes the contact c^{19} or when either subscriber hangs up his telephone, the "c" 95 side of the established circuit is grounded thereby restoring the transmitting switch apparatus, as described by means of the relay M^4 , and at the same time establishing a circuit from the grounded current generator 100 D^4 , over the supply wire e^{51} , relay M^5 , to the wire c^4 of the receiving trunk line R_t which has been connected to the calling subscriber. The relay M^5 attracts its armature e^{44} , which causes the insulating wedge e^{45} to open the 105 normally closed contacts e^{18} thereby cutting off the current from the coils i^2 of the receiving switch magnet. So that when the "c" side of the circuit is grounded as described the receiving switch as well as the transmitting switch is released, and by assuming its normal position disconnects the calling subscriber from the receiving trunk line R_t .

110 Summing up the operations already described, they are briefly as follows: Referring to Fig. 1, subscriber No. 201 for example, desires connection with another subscriber No. 322 for example.

115 Subscriber No. 201 removes his telephone from its switch lever thus establishing a connection over a receiving trunk line R_t^2 for example, to the operator at board No. 2 to which the receiving trunk line is connected. The trunk line indicator c^{13} indicates the call, and the operator removes the plug P from its resting place thus introducing the operator's telephone set into the trunk line and restoring the indicator c^{13} to its normal condition.

The subscriber in the usual manner, informs the operator that he wishes to talk with No. 322. The operator thus connects the trunk line plug to a transmitting trunk line T_3^a for example, at a trunk switch section numbered "3", and by operating her commutator outfit causes that trunk line to be connected to the desired subscriber. She does not select a transmitting trunk line in 5 use at another board on account of a multiple switchboard "busy" test which will be described later. The operator then turns her cord switch lever P^2 and gives her attention to other calls. The indicator c^{13} at 10 once indicates whether the desired connection has been established and if it has been, the called subscriber's bells are automatically rung. If the called subscriber is busy, the calling subscriber may wait with his telephone at his ear, for the desired connection, or he may drop his telephone and return to his work, in which case, when the called subscriber is through the connection between the called and the calling subscriber is automatically established and the bells of both 20 rung.

When either subscriber hangs up his telephone, he disconnects the entire circuit, and the indicator c^{13} at central releases its flap, 30 informing the operator of the disconnection. If both subscribers should by accident fail to operate the restoring apparatus of the sub-central switches, the operator may, as soon as she ascertains this fact by listening 35 in, restore the apparatus by closing the contacts c^{19} .

Fig. 3 shows a test system which may be used with my invention, although it is obvious that any suitable test system may be 40 used in its place. Two boards are shown, board 2 and board 3. At each board is a spring jack J , for each of two transmitting trunk lines Tt^2 and Tt^3 . Each jack contains the contacts c^5 and d^5 already described, and a third contact j . The test contact j of all the jacks connected to a transmitting trunk line are connected together by a test wire j^2 . Each contact j is connected to a test battery J' through individual coils or 50 lamps j' , and the other pole of the test battery is connected to a third contact J^2 on the plug P of each receiving trunk line. The plug also has contacts c^6 and d^6 already described. The contacts in Fig. 3, 55 are somewhat differently arranged from the contacts in Fig. 1. This arrangement lies within the skill of the electrical engineer. When a plug is inserted in a jack as shown, a circuit is established from the 60 battery J' over wire j^4 to the contact j of the jack connected to, by way of wire j^2 to the contact j of all the other jacks of the line, thence in series from the contact j of each jack through the coils or lamps j' of 65 each jack, to the test battery J' .

In Fig. 5 is shown one form of the jack J . This jack has a test contact j , the two line contacts c^5 and d^5 mounted upon the insulated support of an incandescent lamp j' , but insulated therefrom. This lamp j' is a 70 small lamp of the Edison or any other type, and is mounted to the rear of the switch hole and just beyond the reach of the plug P . Each lamp is preferably provided with a reflector j^5 adapted to reflect the light 75 strongly out of the switch hole of its jack, and out of no other switch hole. The reflector may be mercury on the glass itself, and a projecting tube j^6 provided to exclude the light from other jacks. 80

In Fig. 6 there is another form of jack. In this figure the lamp j' is inclosed in a long reflecting or non-reflecting cylinder j^7 adapted to exclude the light from other jack holes. The jack contacts c^5 and d^5 and 85 j may be mounted in any suitable way. In Fig. 7 is a third form of jack. In this jack is a coil j^8 having an aperture j^9 to permit the passage of light from one or more lamps j^{10} with reflectors j^{11} . The lamps and reflectors, one or both, may be individual to each jack, or common to two or more jacks, and should be constantly burning, so that normally the jacks are lighted. When, however, the coil j^8 is energized by a closed test 95 circuit as described, the core j^{12} attracts the magnetic finger j^{13} , attracting the flap j^{14} shutting off the light from the jack hole, rendering it dark, which in this form of 90 jack, indicates the line to be "busy." 100

I prefer however the forms shown in Figs. 5 and 6. Although I show this jack for a busy test, that is, to show that a subscriber is to begin conversation, that a conversation is in progress, or that it is over, it is obvious 105 that it may be used for other purposes, that is, for calling, for clearing out, for trunk line signal work, and various similar purposes.

In Fig. 4 are shown a number of jacks, 110 three of which indicate "busy." This is a section of one of the switchboards to which all the transmitting trunk lines of group No. 2, are connected. By inserting a plug in any one of these jacks, the operator controls a connection between a transmitting trunk line and any subscriber of the 115 200 group.

The switchboard is divided into sections similar to this. To each section are connected the transmitting trunk lines of a different group of subscribers, and each section is marked with the appropriate number of the group. 120

It has already been described how a transmitting switch is operated. Fig. 8 shows more completely the circuits by which this is accomplished. This switch shows in plan view the sets of contacts of a hundred subscribers. Upon the switch are ring contacts 125 130

*c*² and *d*² common to all the subscribers of the group and connected to the trunk line conductors *c*⁴ and *d*⁴ as shown in Figs. 2 and 12. The line wires *ab* of each subscriber are connected to a different pair of contacts *c'* and *d'*.

The contacts *c*¹¹ and *c*¹⁵ are connected to the wires *c*²² and *c*²³ and *c*⁴¹ respectively, there being a different set of those wires for each subscriber as shown. There are ten contacts *c*¹⁶, one of these contacts being common to ten subscribers. Each contact *c*¹⁶ is connected to a contact upon switch *m*¹³. The contact *c*¹⁶ numbered 0 is connected to the contact marked 0 upon the switch *m*¹³. The contact *c*¹⁶ numbered 1, is connected to the contact *m*¹³ numbered 1, etc. The contacts *c*⁴⁰ are connected to the contacts of the switch *m*¹⁰. Contacts *c*⁴⁰ numbered 0 are connected to contacts 0 of the switch. Contacts numbered 1 are connected to contact No. 1 of the switch, etc. The set of contacts belonging to each subscriber comprises individual contacts *c'*, *d'*, *c*²¹, *c*¹⁵ and *c*⁴⁰. The ring contacts *c*² and *d*² are common to all the subscribers connected to the switch. Each contact *c*¹⁶ is common to a different set of ten subscribers. Contact 0 for example, is common to subscribers 0 to 9 of the group. Contact 3, for example, is common to subscribers 30 to 39 of the group, etc. So that the switch *m*¹⁰ selects the unit of a subscriber's number and the switch *m*¹³ selects the tens thereof. For each subscriber there are separate contacts *c*²⁵ and resistance *e*¹¹.

The functions of the circuits and apparatus have already been shown in connection with Figs. 1 and 2.

Fig. 9 shows the operator's commutator outfit already described or illustrated in diagram in Fig. 1. Upon a plate of insulating material *C*⁹ are mounted cross strips of conducting material *d*¹⁸. Through each strip *d*¹⁸ project push buttons *C*¹⁰, so mounted as to slide up and down through the strip and through the support *C*⁹. The strips *d*¹⁸ are separated from each other by insulating material *C*¹¹. Each push button *C*¹⁰ has around its neck a spring *C*¹², one end of which is soldered to the push button and the other end soldered to the strip upon which the push button is mounted. This soldering is not necessary but is preferred on account of the good electrical connection which results therefrom. The lower end of each push button is provided with a point and hollow portion *C*¹³ and when a button is pressed down as shown at *C*¹⁴ it separates two conducting bars, *C*¹⁵ and *c*¹⁸ thereby separating them and then by means of the hollow described permits them to return almost to their normal position, holding the push button in its operative position. When another push button is depressed and the bars are again separated this push button

*C*¹⁴ is released and the other one is held in its place. If the same push button is again depressed it will spring back as far as the notch *C*¹³ and there be held a second time. The bars *c*¹⁸ are at each end mounted upon 70 but insulated from a support *C*¹⁶, which is connected to the insulating plate by toggle-joints, *C*¹⁷. Thus these bars with their support form a kind of gridiron. The mounting of but one corner of this gridiron is 75 shown but the other three corners are similarly mounted.

The conducting bars *C*¹⁵ are at both ends mounted upon and electrically connected with a support *C*¹⁸¹ which is mounted by 80 means of toggle-joints *C*¹⁹ upon the insulating plate *C*⁹. A cord *C*³³ attached to the toggle-joints *C*¹⁹, running over the pulley *C*³⁴, and connected through a spring *C*³⁵ to a weight *C*²⁰, holds these gridirons in their 85 normal position with the post *c*³⁶ touching the toggle-joints, to keep them in a normal position.

Pivoted upon the bar *C*⁵ is a lever *C*²¹, one end of which is pivoted to the movable bar 90 *C*¹⁸¹ and the other end of which carries an insulated stop *C*²². Against this stop normally rests a stud or roller *C*²³, secured to the commutator wheel *C*, holding the commutator in its normal position. When a 95 push button *C*¹⁴ is depressed, it moves the bars *C*¹⁵ mounted upon the cross bars *C*¹⁸ which in turn causes the lever *C*²¹ to remove the stop *C*²² from beneath the roller *C*²³, releasing the commutator wheel *C*. A key *C*²⁴ 100 with studs *C*²⁵ causes the friction clutch *C*²⁶ to turn on its axis *C*²⁷ and by means of the spring connection *C*²⁸ causes the commutator wheel *C* to turn in the direction of the arrow. As the bar *C*¹⁸¹ returns at once to its normal 105 position when a push button has completed its downward movement, the catch *C*²² is restored to its first position so that when the commutator *C* has completed a rotation the stud or roller *C*²³ will prevent it from 110 turning any farther. The shaft *C*²⁷ may be used in common for several or all commutators, and is regulated to prevent a too rapid motion of the commutator. The commutator wheel *C* is mounted loosely upon the 115 shaft *C*²⁷ but prevented from longitudinal movement. The shaft *C*²⁷ is rigidly connected to the key *C*²⁴.

Upon the body of the commutator *C* are mounted the posts or rods *g'* adapted to cross connect the strips *c*¹⁴ and *d*¹⁴ with the contact springs *c*¹⁷ and *d*¹⁷ respectively. The last rod *g''* to pass under the springs is so wide as to electrically connect all of the springs simultaneously to the strips *c*¹⁴ and *d*¹⁴. The rods *g''* are double, and have cuts so that one rod affects or strikes only spring contacts *c*¹⁷, and the other rod strikes contacts *d*¹⁷. The rods *g''* are so related to the springs that all the springs *c*¹⁷ and *d*¹⁷ 130

strike and make contact with their respective strips at the same time.

The rods g' , g'' correspond to the strips g' , g'' in Fig. 1. The construction of these strips and springs and coöperating parts is better shown in Fig. 14. As the posts or rods g' , g'' strike the rollers c^{12} the springs upon which the rollers are mounted are forced into contact with their respective contact springs c^{14} and d^{14} . The springs normally rest upon rod C^{29} covered preferably with ordinary soft rubber tubing. This rod is mounted at each end upon a pivoted arm C^{30} pivoted at C^{31} to the insulated support C^{28} . A screw C^{32} working in a threaded hole in the arm C^{30} and against the fixed plate C^{37} adjusts the position of the rollers with relation to the commutator rods.

The strips c^{14} and d^{14} are mounted upon an insulated support C^{40} which is connected at either end to a supporting spring C^{38} , which in turn is mounted upon the base C^{28} .

Through each spring C^{38} passes the shank of a screw C^{41} having its threaded end working in a threaded hole in a rigid support C^{29} . In this manner the proximity of the strips to the contact springs may be from time to time adjusted to allow for wear, and so forth. The function of these parts has already been described. The purpose of this figure is simply to show the preferred mechanical construction of the commutator outfit.

Upon a push button C^{10} is mounted a pin C^{50} playing in a slot C^{51} . There may be a separate slot C^{51} for each push button.

A portion of the keyboard is shown. The other parts are omitted as they are mere duplication.

There are intended to be ten rows each containing ten buttons, adapted to make one hundred different combinations, as illustrated in diagram in Fig. 1, and wired as shown in that figure. Instead of a separate button for each number there may be one button only adapted to be inserted in any one of one hundred holes. This button would be substantially then a plug. Such a plug should have a handle. The hollow in the lower end is necessary.

In Figs. 10 and 11 are shown some of the details of the construction of the transmitting switch apparatus, that is, the apparatus that controls the operation of a transmitting trunk terminal switch. In connection with Fig. 2 this apparatus has been described with relation to its electrical features, and now it is the purpose to set forth some of the preferred mechanical details. Some of the details such as back stops and so forth are omitted because of the danger of rendering the drawings unintelligible from complexity.

Upon the arbor or shaft n^{12} , which is

mounted loosely or rigidly in end supports m^{27} are loosely mounted ratchet wheels m^{28} , n' , m^{29} . These wheels are in electrical connection with the arbor, and are provided with suitable devices to prevent longitudinal motion thereon.

The ratchet wheel n^{11} for the circuit controller C^2 is shown in side view in Fig. 10. Upon its faces are projections n , n^{51} , n^{52} on one side and n^2 , n^3 on the other side, adapted to act on rollers n^7 mounted on contact springs n^{14} , which are adapted to open and close the pairs of contacts n , n' , n^3 , n^4 , n^5 , n^6 , as shown in Fig. 2.

It is operated by a pawl m^6 in the direction of the arrow in its forward movement. The pawl m^6 is pivoted upon a lever r^7 which in turn is pivoted upon a suitable rigid support r^8 . The pawl m^6 is provided with a roller r^6 which engages with the tooth next below its normal position (shown), and forces the tooth upward under the influence of the weight r . The fixed roller r^4 acting on the arm r^5 of the pawl so guides the pawl that it may slide into position to engage a ratchet tooth, and when the tooth moves the wheel forward, is guided out of engagement with the tooth at the moment that the detent r^9 engages the next tooth for detention. The roller r^4 also prevents further useless upward movement of the pawl. This roller r^4 may permit the pawl to remain in the ratchet wheel and by a mechanical connection with the detent withdraw the pawl from the ratchet wheel while restoring, as indicated in Fig. 17. The weight r attached to the arm r^5 of the pawl tends to draw the pawl into engagement with the ratchet teeth, yet is strongly counteracted normally (or when the lever r^7 is not subjected to an outside or magnetic force) by the weight hung upon the lever r^7 .

The detent r^9 is mounted upon a suitable pivoting support m^{24} , and upon its heel m^{29} is provided with the insulating wedge m^{20} adapted to open contacts e^{31} and e^{33} , but this opening does not happen until the detent has been withdrawn to its extreme position by the magnet M^4 . This is due to the flexibility of the springs resting against the wedge m^{20} .

Upon the detent r^9 is mounted a slot m^{18} in which plays a rod r^{10} which in turn is carried by the armature m^{17} so that when the armature is drawn up by the magnet M^4 it withdraws the detent r^9 from the ratchet wheel, permitting the latter to return to its normal position. The slot m^{18} is sufficiently long to permit the detent to play over the ratchet teeth in their progress forward without affecting the rod r^{10} . The lifting of armature m^{17} by the magnet closes contacts m , the function of these contacts being described in connection with Fig. 2; namely to hold the detent up until the wheel is re-

turned to its normal position. The wheel is provided with a pulley m^{28} upon which a restoring weight r is hung by means of a spring r' and cord r^2 .

5 Upon the pawl m^6 , see Fig. 11, is pivoted a cross bar e^{34} , having loose engagements r^{11} with the ends of the armatures r^{12} , pivoted at r^{13} , and acting under the influence of magnets e^9 and e^7 . The armatures r^{12} have 10 pawl movements m^8 , m^{11} , like that shown and described in Fig. 10 for the controller C^2 .

These pawl movements actuate the ratchet wheels m^{28} , upon each of which is mounted 15 an arm m^8 and m^{12} adapted to sweep over and make contact with studs 0-9 shown in Fig. 2. In Fig. 11, only stud m^{63} is shown for convenience, on each switch m^{10} and m^{13} .

These ratchet wheels also have pulleys 20 m^{28} with their cord springs and weights r , r' and r^2 . They are also provided with detents m' and m^{19} having slots m^{18} in which works the rod r^{10} which withdraws the detent from their engagements with the ratchet- 25 sets. Upon the hub of the ratchet wheel n^{11} is a bar m^3 normally resting against the upper side of the pivoted cross bar or link e^{34} . When this switching apparatus is operated, first the magnet e^9 is operated once, then the 30 two magnets are operated alternately a determined number of times, to correspond with the units and tens of the number signaled, and then the two magnets are operated simultaneously by the double rod g'' shown in Fig. 9. When magnet e^9 is operated the first time it draws down the pawl m^6 so that it engages with the proper tooth, and at the same time tips the link e^{34} so that the other end of the link the right end in 40 the figure, strikes against the bar m^3 and the further movement of the link forces the pawl m^6 downward so that it engages with the next tooth for operating purposes. When the current leaves the magnet e^9 the pawls lift upward again under the influence of 45 their weights r , and advance the two ratchet wheels one tooth, where they are held by the detents. The succeeding alternating im- 50 pulses over the magnets and the correspond- 55 ing sides of the metallic circuit advance the two wheels m^{28} and their switch arms m^9 to their appropriate positions, but do not af- fect the pawl m^6 on account of the lost mo- tion of the link connections r^{11} , and on ac- 60 count of the different position for the stop bar m^3 due to the advance of the ratchet wheel n^{11} to which it is rigidly connected. Finally however the impulses wind up with 65 simultaneous ones, one in each magnet and together they again draw the pawl m^6 down sufficiently to engage with the next tooth of the ratchet wheel n^{11} , thus advancing it another step into its third and final position. The condition of the contacts n , n' , n^3 , n^4 , n^5 and n^6 in these three positions have already

been described in connection with Fig. 2, and it is not necessary to repeat here. It is enough to say that the projection upon the two faces of the wheel n^{11} should be so placed and gaged as to accurately perform 70 their proper functions.

Upon insulating supports n^{18} are mounted spring contacts m^{60} and m^{62} normally out of engagement with the flanges of the respective pulleys m^{28} on account of cuts or depre- 75 sions at m^{61} and m^{100} respectively, but when the wheels are not in their normal position these springs are in contact with the flanges. This closes the circuit to ground from the springs to the grounded supports m^{27} for 80 the purpose of retaining the armature m^{17} in its active position until the wheels are all restored, as fully described in connection with Fig. 2.

Upon insulating supports n^{15} are mounted 85 the studs with which the contact springs n^{14} come into contact when operated by the circuit controlling ratchet n^{11} to close the contacts of the controller.

Fig. 12 shows in side view a modified and 90 preferred form of a transmitting trunk line switch already described in connection with Fig. 2 and Fig. 8. Upon a shaft f adapted to be rotated under the influence of some kind of motor is rigidly connected a collar 95 h^5 . This collar supports on the shaft the loosely mounted collar h^6 . Upon the shaft f is also mounted rigidly a second sleeve h^7 and also the yoke h^8 of the coils h^2 as also shown in Fig. 18. Each armature yoke h^8 100 on the shaft is rigidly connected thereto, and acts as armature for the magnet coils sus- pended below it. Each coil has a pole h^9 so shaped as to attract a ring armature h^2 .

The poles h^9 bear against a shoulder h^{10} 105 rigidly connected to the loosely mounted sleeve h^6 . The ring armature h^2 has an aperture sufficiently large to permit it to work up and down over the sleeve h^6 . When this ring armature is in its upper position, 110 it impinges against the shoulder h^{10} and is thereby prevented from coming into contact with the poles h^9 of the magnet, which at the time may be rotating under the in- 115 fluence of the shaft and motor. The armature h^2 is pivoted at h^{11} upon an upright support h^{12} which is mounted upon the switch arm h' . The switch arm is rigidly connected to the sleeve h^6 . Connected to the armature h^2 is a catch h^3 normally en- 120 gaged with a catch h^4 rigidly connected to the collar h^5 . When the armature h^2 is not attracted the catch h^4 drives the switch arm h' and all parts mounted thereon in the di- 125 rection in which it rotates. When the catch h^3 leaves the catch h^4 the switch arm h' stops its rotation, while the shaft f , the col- 130 lar h^5 , the sleeve h^6 and the coils h^2 continue to rotate as long as they are influenced by the motor. Upon the switch arm h' are 130

mounted the contact springs i' , i^5 and i^6 . The contact spring i^6 is electrically connected with the switch arm, but the others are insulated therefrom except for the electrical connections. These springs play over the contacts e^{40} , e^{16} and e^{15} , whose functions have already been described. Mounted upon but insulated from the armature h^2 are two hollow rods h , one of which carries a bridging contact d^3 , the other of which carries a similar contact c^3 . These bridging contacts are pivotally mounted upon the bars h . The upper end of each of these contacts normally rests against stop h^{13} under the influence of springs h^{14} .

One end of each spring h^{14} is fastened to the bar around which it is coiled, and the other end of the spring is connected to the upper end of the contact mounted upon the bar. One bar h has an extension h^{15} which is guided by a properly formed guide piece h^{16} , which is mounted upon but electrically insulated from the switchboard h^{17} . Mounted upon but electrically insulated from the bars h is a spring contact i^7 adapted to make connections with any one of a number of contacts e^{21} around the switchboard.

Upon the support h^{12} are mounted two contact springs h^{18} adapted to make sliding contact with round annular rings h^{19} mounted upon coils i^2 of the magnet. These rings h^{19} form the terminals of the magnet coils. One contact spring h^{18} is connected by means of wires i to the contact springs i' and i^5 . The other contact spring h^{18} is connected by means of wire i^3 to contact spring i^6 . A receiving trunk line switch is identical in construction with the transmitting switch shown in Fig. 12, except for the extra contact e^{40} , spring i^6 , the construction of contacts e^{16} , and the electrical connections. This difference is well shown and described in connection with Fig. 2.

The circuit closing apparatus in Fig. 12 is shown in its active position. Normally the weight of the armature h^2 causes the catch h^3 to engage with the catch h^4 and the contacts c^3 , d^3 and i^7 to be out of connection with their respective switchboard contacts.

Fig. 13 shows a top perspective view of the apparatus shown in Fig. 12, or at least a part of this apparatus. The sets of contacts of the various subscribers are shown, and the serrated edge h^{16} which guides the end h^{15} so that the circuit closers c^3 and d^3 make proper connections with contacts c' and d' . It is also shown how the contact springs i' , i^6 and i^5 make connection with successive sets of contacts. The moment the spring leaves one set of contacts they make electrical connections with the next set of contacts, so that the circuit closer h is allowed considerable time to descend into place.

Upon the circuit closing bars h is shown

the contact spring i^7 mounted upon insulating material. This spring i^7 is so adjusted that it will slide easily into place.

When the coils i^2 of this switch are energized over the circuit which has already been described, the armature h^2 is attracted by the poles h^9 causing the end h^{15} to strike the serrated guide h^{16} and steer the contacts c^3 and d^3 into such a position that they will make proper connections. In Fig. 12 it is shown how the two ends of the pivoted contacts c^3 and d^3 bear against their appropriate contact surfaces. By means of this construction these contact pieces have a frictional action in attaining their position and an equal amount of pressure is brought to bear upon each of the four pairs of contacts.

Normally these circuit controllers rotate with the shaft f . They may travel over the switchboard at the rate of at least one rotation in three seconds. This speed has been found successful with solid core slow-acting magnets, but with quicker acting magnets a higher speed may be attained.

In Fig. 15, is shown a side view of the operator's cord switch, the front view being shown in Fig. 1. The lever P^2 is pivoted at P^8 , and is provided with a base P' , upon which the plug normally rests. A spring P^7 having bends P^8 working on the edge of the base tends to hold the base in its upper or lower portion against the stops P^{10} . The operator may tip the lever P^2 into its upper or lower position, thereby altering the circuit connections as described in connection with Fig. 1.

The generator D^3 which supplies the current for restoring the system should supply a direct current preferably so toned down by electromagnetic resistance and shunted by condensers as to be inaudible in the receivers by induction. It should be so toned as to be inaudible in the receivers in the manner well known to electrical engineers, by impedances and condensers, and the subscribers' bells a' so constructed as to respond thereto. The current may be direct, and the bells of the circuit breaking variety; or the current may be alternating of a periodicity below 16 pulsations a second, and with the intermission between the pulsation less than one hundredth of a second in length. This nature of current I prefer. When developed from a dynamo, and its irregularities properly toned down, it acts satisfactorily both as calling and signaling current.

The operation of the exchange with a current supply of this character is as follows:

A subscriber desiring a connection takes down his receiver, thus permitting his switch to ground the "b" side of his metallic circuit, and operating the first receiving switch whose contact springs pass over this subscriber's set of contacts. As these switches are spirally arranged with respect to the

various sets of contacts of this subscriber, as shown in diagram in Fig. 1, but one receiving switch will operate.

This receiving switch making connection 5 with the calling subscriber's circuit closes a complete metallic circuit from the central station to the subscriber's station, including the subscriber's telephone set, the metallic circuit conductors of the subscriber, and the 10 metallic conductors of the receiving trunk lines, between which is bridged the current generator CG, including a call annunciator c^{13} . The current from the generator operates this call annunciator over the circuit described, calling the attention of the operator 15 to this receiving trunk line.

The operation of the receiving switch has prevented the possibility of the calling subscriber's line being connected with any other 20 trunk line, and the telephone switch of the subscriber has closed the telephone circuit.

The operator, seeing the call annunciator display a signal, takes up the plug of the trunk line associated therewith and this cuts 25 her telephone set into circuit, to find out the number of the called subscriber. Having learned the number she inserts the plug into the jack at her board of a transmitting trunk line running to the group to which the called 30 subscriber belongs, and depresses a button c^{10} of her commutator outfit shown in Fig 9, causing the metallic conductors of the transmitting trunk line to make connection by means of the switch apparatus shown in Figs. 35 2 and 11 with the metallic conductors of the called subscriber's circuit. This connection will take place only when the called subscriber is free.

When the operator has thus inserted the 40 plug in a jack and presses her commutator button, she tilts the switch p^2 into the third position already described, and leaves the lines to take care of themselves.

If the called subscriber is free, the transmitting trunk line will immediately connect 45 itself thereto. The tilting of the operator's switch P^2 has cut the current from the receiving trunk line circuit just described and introduces it and the annunciator C^{13} into the 50 circuit of the transmitting trunk line as described, so that when the metallic circuit of the trunk line is connected to the called subscriber's line, this generator is in a complete metallic circuit, and the annunciator c^{13} is again energized indicating to the operator 55 that the called subscriber's line is accessible. With the relay d^{13} it closes the metallic conductors of the receiving trunk line connected to the calling subscriber, thus completing a metallic circuit for conversation.

When the current traverses the circuit of the called subscriber it operates his call bells as long as his telephone is not switched for use. When he answers the call this current 65 is inaudible in his telephone.

The closing of contacts c^{12} and d^{12} by the annunciator also closes the circuit of the generator CG to the circuit of the calling subscriber again, and if he has dropped his telephone and returned to work leaving the 70 contacts a^{16} and a^{17} closed to each other, ringing his call bell a' informing him that his order has been fulfilled and that he has been connected to the called subscriber.

The circuit may be supervised by the 75 operator who has established these connections by looping or bridging her telephone set into the circuit as already described.

The pulsations of the alternating current CG are preferably so slow as not to cause 80 annoyance to the called subscriber. Five or six pulsations to the second is quite sufficient for the purpose of calling and signaling.

When conversation is over, and the subscribers have no further use for the metallic circuit which has been described the subscribers hang their telephones upon their switches thereby grounding the "a-c" side 85 of their metallic circuit. This ground connection may be effected by either subscriber or by both. That is, when the "a" side of the circuit is grounded by the first subscriber who hangs up his telephone, or by both when they both hang up their telephones together, the relays M^4 and M^5 are operated 90 as has been described with relation to Fig. 2, and the switches at the sub-central or, in other words, the transmitting and receiving trunk line switches, are released, and the 100 connection between the subscribers' metallic circuits and the trunk line metallic circuits is opened by the disconnected contacts c^8 and d^8 thereby opening the circuit of the generator current from CG, and releasing 105 the flap of the annunciator c^{13} indicating to the operator at the central station that the trunk lines are no longer in use. She then withdraws the receiving trunk line plug 110 from the jack of the transmitting trunk line jack, and returns the plug to its normal resting place on the insulated support P' , at the same time pressing this support back to its normal position shown in connection with the receiving trunk line R^2 .

The relay M^5 opens the contacts e^{18} of the receiving trunk line switch.

The restoring circuit operates magnet M^4 which as will be seen in Fig. 11, releases the apparatus controlling the transmitting 120 switch. The contacts n^4 are opened by the circuit controller C^2 thus opening the circuit of the coils i^2 of the transmitting switch, whereby that switch resumes its normal position, and if the shaft f is rotating, it continues to rotate with it.

The speed with which a connection is established by my system depends upon the speed of rotation of the transmitting and receiving switches, and the speed with 125

which the apparatus controlling transmitting switches is operated by the operator's commutator outfit.

As the first one of the spirally arranged receiving trunk switches closes a subscriber's circuit to central, this circuit is closed almost instantaneously. When the exchange is at its busiest time, this connection cannot be delayed more than two seconds at the outside, so that when a subscriber takes down his telephone from its switch, the connection to central is established, and the call annunciator operated before the receiver reaches his ear. The operator's telephone is cut in by her taking up the trunk line plug, and this is done in the usual manner, except that it is done more quickly than when the operator has to insert a plug into the jack of a calling subscriber. This operation is saved by my system. After inserting the plug into the jack of the proper transmitting trunk line, and at a glance she can see what trunk line is not busy, she presses down one of her commutator buttons C^{10} and after one or two seconds tilts the handle of her switch P^2 . This is plenty of time for the apparatus to be operated for controlling the transmitting trunk switch, for one second I find is the outside limit for the maximum number of impulses to be sent over each side of the metallic circuit, so that the time which has been consumed between the moment when the subscriber took down his receiver to the moment when the operator has finished her part in establishing the desired connection is at the outside not more than four seconds, and is generally not more than two or three seconds. The operator's share of this time is still less.

If the called subscriber is free the connection to his line will be almost instantaneous, never more than two seconds later, and this connection is indicated to the operator. If, during the busy hours of the exchange, the operator has other connections to establish she can at once turn her attention to them. If the called subscriber is busy, the indicator will not operate, and she will know that the connection has not been established. She can then loop or bridge her telephone into the circuit and tell the calling subscriber that he may drop his telephone, and that he will be called when the called subscriber is free. The calling is automatically effected without further attention of the operator when the called subscriber is "free". If the indicator tells her that the connection has not been established after some time, and the trunk line is needed, the operator may close a pair of extra contacts c^{10} and withdraw the plug from the jack, leaving the trunk lines and trunk switches in their normal position.

It will be seen that my invention saves

a great deal of time on the part of the central operator.

For an exchange of ten thousand subscribers having a single central station, each board of the systems now in use requires a jack for each subscriber and about one hundred annunciators. A dozen or fifteen clearing-out annunciators are also used.

In my exchange, the jacks are reduced from 10,000 in number to 1200 or 1500, the calling annunciators are entirely omitted, and about 12 or 15 annunciators used for both calling and clearing-out.

In systems now in use, 24 to 30 plugs are required for each operator. In my system the plugs are reduced to one half the number.

In systems now in use, the metallic circuits of the above exchange would be 10,000 in number, and each one would reach from the subscriber's station to the central office. In my system these circuits are reduced to about 1000 to 2500 in number for the greater part of the distance.

To obtain these advantages requires that each operator shall have a commutator outfit like that shown in Fig. 9 and that from 10 to 25 trunk line switches be located at some outlying points in proximity to groups of subscribers. That is, each group of subscribers shall have a few switches in some place in their locality. These are the only additions required by my system.

It is obvious that single circuit lines may be organized into an exchange of this kind, and that by slight alterations two or more subscribers may use the same individual circuit. For the latter arrangement suitable automatic calls should be provided under the control of the operator.

It is obvious that the subscribers may be called manually by the operator in the usual way, both with two or more subscribers on an individual circuit, or with but one subscriber on each circuit. But the automatic feature saves time.

It is also obvious that some of the circuits, those whose subscribers are in close proximity to the exchange, may each have appropriate jacks at the exchange, with suitable busy test, adapted to be directly connected to receiving trunk lines. Such an arrangement requires the usual plug outfit, with some additions, described in another application.

One double plug outfit may occasionally be of use to the operator to connect together two lines that have not just called. Such an outfit is composed of two plugs each provided with the switch apparatus shown in Fig. 1 in connection with trunk line Rt^2 , and they must be connected together where these outfits join the trunk line conductors.

In the following claims I shall make use

of the term "side switch" by which is to be understood a commutator or equivalent device for controlling and directing the application of current to one or the other actuating elements of the main switch, as for example the commutator used in combination with the units and tens elements hereinbefore described.

For convenience I may also make use of 10 the expressions "double element selection" and "two-element selection." By this, I mean that the selection of a unit in a given group is made by double selection of the group and the unit in the group. While my 15 switch hereinbefore described is specifically a single motion switch, it is conceivable that the same general method of functioning might be applied to what is known in the art as the two-motion switch, viz. one in 20 which the switch arms move in two different directions, as vertically and horizontally.

I do not want to limit the use of my invention to the exact apparatus or circuits shown, for it is obvious that wide variations 25 may be made from them and still the general results obtained.

Having thus described my invention what I claim and desire to secure by Letters Patent is:

30 1. An electrical impulse sending machine for telephone exchange systems comprising two sets of a plurality of pairs of complementary contacts, the complementary contacts of each pair comprising a stationary and a movable contact, cam engaging pro-

jections carried by the movable contacts, a rotatable cam carriage, and a plurality of cams carried by said cam carriage and so proportioned and arranged in relation to said cam engaging projections as to cause 40 the movable contacts of each of said pairs of contacts to be successively operated a different given number of times during a complete revolution of said carriage, said sets of contacts being so arranged in relation 45 to the cams that the different sets will be actuated alternately, one of said cams being arranged to actuate both sets of contacts simultaneously.

2. An electrical impulse sending machine 50 as described in claim 1 together with an impulse selecting device comprising a group of conductor bars arranged parallel to each other and equal in number to the pairs of complementary contacts, each bar being electrically connected to one of the said complementary contacts of each of said pairs respectively, a second group of parallel conductor bars equal in number to the pairs of contacts, each bar in said second group 55 extending across all the bars in said first group and out of electrical contact therewith, each bar of said second group being connected respectively with one of the complementary contacts of each of said pairs, and means 60 for electrically connecting any one of the bars of one group with any one of the other group.

In testimony whereof I affix my signature.
MYRON F. HILL.
